UNITED STATES PATENT OFFICE.

JOHN H. BARTLETT, OF OSHKOSH, WISCONSIN, ASSIGNOR TO THE OSHKOSH TRUNK COMPANY, OF OSHKOSH, WISCONSIN, A CORPORATION OF WISCONSIN.

SHOE-HOLDER FOR TRUNKS.

1,262,911.

Specification of Letters Patent. Patented Apr. 16, 1918.

Application filed November 22, 1916. Serial No. 132,853.

To all whom it may concern:

Be it known that I, JOHN H. BARTLETT, a citizen of the United States, residing at Oshkosh, in the county of Winnebago and State of Wisconsin, have invented new and useful Improvements in Shoe-Holders for Trunks, of which the following is a specification.

This invention relates to shoe holders for trunks, and more particularly for trunks of the wardrobe type.

Among the objects of my invention is to improve the construction of shoe holders of the kind referred to, in the several particulars, as will hereinafter more fully appear, and to provide in particular a shoe holder that may be readily and quickly removed from the trunk for the purpose of not only cleaning the shoe holder, but also the portion of the trunk occupied thereby, and thus maintain both in a clean and sanitary condition.

The invention consists further in the matters hereinafter described, and more particularly pointed out in the appended claims.

In the accompanying drawings:

Figure 1 is a perspective view looking into an open wardrobe trunk containing a shoe holder embodying the features of my invention, the cover of the shoe holder being shown in its closed position and broken partially away;

Fig. 2 is a vertical sectional view taken on line 2-2 of Fig. 1, the cover of the shoe holder being shown in its closed position;

Fig. 3 is a fragmentary perspective view looking into one of the lower corners of the wardrobe section and showing the groove for receiving one of the edges of the shoe holder;

Fig. 4 is a perspective view of the shoe holder removed from the trunk;

Fig. 5 is a sectional view taken on line 5-5 of Fig. 4; and

Fig. 6 is a sectional view taken on line 6-6 of said Fig. 4.

In said drawings, I have shown in detail one preferred form of shoe holder device embodying the features of my invention and as being applied to a wardrobe type of trunk, which, as illustrated, comprises two vertical, hinged together sections 10 and 11, one constituting the wardrobe section of the trunk and the other the drawer section thereof.

As illustrated, the section 10 constitutes the wardrobe section of the trunk, in that the

extensible trolleys 12, 12, the garment hangers 13, 13, and the adjustable follower 14 are all located in their proper positions in the upper part of said section 10, while the other section 11 contains a tier of movable drawers or like containers 15, 15.

As shown in Fig. 4, said shoe holder comprises a flat, rectangular base-board 16, preferably made of wood or any other suitably stiff material. Extending lengthwise across one side of said base board 16 is a flat strip 17, made of a suitable, relatively stiff material and being corrugated or bent to provide a plurality of outwardly bowed or loop-shaped sections 18, adapted to form, with the base-board therebehind, a plurality of open-ended, shoe-receiving spaces or "pockets" 19, 19. The strip 17 is made considerably narrower than the width of the base-board 16 and extends centrally across the same, so that the shoes may be inserted toe first into said "pockets" 19 from either open end thereof. Thus the base-board 16 may be placed in the trunk with either longitudinal edge thereof uppermost. As shown in Fig. 6, the ends of said strip 17 are folded over and around the end edges of the base-board, and are secured to the rear side thereof by fastening members or rivets 20. Said strip 17 is made of a material of such stiffness that when once bent to provide the looped sections 18, the latter will all remain in such form. Each looped section 18 is usually made of such dimensions as to provide a space or "pocket" 19 for receiving but one shoe, and, as shown in the drawings, I have provided four of such pockets. In order to secure the loops 18, 18 to the base-board, I provide a plurality of fastening members in the form of tapes 21, 21, each being of a length to extend across the outer face of the strip 17 at the ends of the bowed sections, that is, where the bowed sections contact with the board. The ends of each tape 21 are inserted through holes 22, 22 in the board, and are bent toward each other and secured to the back of the board by fastening members or rivets 23, 23, as shown in Figs. 5 and 6. Along each longitudinal edge of said base-board 16 are an equal number of holes 24, 24, which form part of the means for detachably holding said base board in the trunk.

As customary in trunks of the kind referred to, the wardrobe section 10 has two

upright side walls 25, 25, an upright rear or back wall 26, and a bottom wall 27. Located in said section 10 and secured to the bottom wall 27 thereof is a strip of wood or cleat 28, the latter extending between the side walls 25, 25 and spaced outward from the back wall 26, so as to provide an upwardly opening groove or channel 29 of a width slightly greater than the thickness of the 10 base-board 16. When inserted in the section 10, said base-board 16 is placed upright and flatwise against the back wall 26 with one of its longitudinal edges seated in the groove 29 and the loops 18, 18 projecting outward. 15 In order to detachably hold the base board in such position, I provide on the back wall 26 a plurality of fastening members, preferably in the form of turn buttons 30, 30, the latter being equal in number to the 20 holes 24 in the upper edge of the base-board. When inserting the base-board in the trunk, the rotatable heads 31 (see Fig. 3) of the turn buttons are in position to readily pass through the holes 24, and when turned into 25 their locking positions, namely, at right angles to the stems of the turn buttons, the latter serve to hold the base-board in the trunk and against the wall 26 thereof, as shown in Figs. 1 and 2. Inasmuch as there 30 are an equal number of holes 24 along each longitudinal edge of the base-board, the latter may be placed on the wardrobe section 10 with either longitudinal edge lowermost and in the groove 29. As shown in Fig. 1, 35 the base-board 16 is made of a length to extend substantially across the wardrobe section, and therefore provide the greatest number of shoe holders 18, 18 permitted by the width of said section. To remove the 40 base-board 16, the rotatable heads of the turn buttons 30, 30 are turned into their unlocking position so as to pass through the adjacent holes 24, 24, and thereupon the board may be readily grasped and completely withdrawn from the trunk. 45

When in the trunk, the shoes are held in the "pockets" 19 with toes extending downward and heels upward, and, no matter how careful the user of the trunk may be in first seeing that the shoes are wiped off before being placed in the holders, yet if the shoes are left uncovered there is a possibility of the lower ends of the delicate and other garments on the hangers 13, 13 being soiled by rubbing against or contacting with the shoes. This is especially true with respect to ladies' garments of that character which are made of fine and delicate material and used for parties, dances, and like formal social occasions. The polish or other material used for shining or cleaning the shoes will readily rub off and produce a smear or smudge on such garments if brought in contact with the shoes, and for avoiding this I provide a protecting flap or

cover 32 for completely inclosing the base-board 16 and the shoes held thereon. Said cover 32 is preferably made of any suitably flexible, textile fabric, and has its lower margin secured to the bottom wall 27. As shown in Figs. 2 and 3, the inner margin of the cover 32 is inserted beneath the cleat 28. Formed in the outer or free edge of the cover 32 are a plurality of holes or eyelets 33, adapted to pass over the turn buttons 30 when the rotatable heads 31 thereof are in unlocked position. The flap 32 is made of such dimensions as to completely cover the base-board 16 and its shoe holders when said flap is closed, and the same is detachably held in such position by the turn buttons 30. Manifestly, before the base-board 16 can be removed from the trunk or inserted therein, the cover flap 32 must be first swung down in its open position, as shown in Fig. 3.

The fact that the shoe holder 16 may be completely removed from the trunk presents numerous advantages. First, it is self evident that the base-board 16, as well as the strip 17, will become soiled by the mud, sand, and the like rubbing or scraping off the shoes, and by having the shoe holder detachably mounted in the trunk, the shoe holder may be readily removed therefrom for the purpose of being brushed off and cleaned. Furthermore, the particles of mud, sand, and the like in being scraped off the shoes will fall and accumulate in the bottom of the trunk behind the cover flap 32 and in the groove 29. Manifestly, by being able to completely remove the shoe holder and open the cover 32, the bottom of the trunk and the groove 29 may be readily and easily cleaned. It follows, therefore, that the shoe holder and the bottom of the trunk may be kept clean and sanitary. Then again, the cover flap 32 being secured along its lower edge, the cover may be swung down against the bottom wall of the trunk and be in the most convenient position for being brushed off and cleaned. Moreover the cover flap 32 being secured to the bottom wall 27, said cover flap may be dropped into its open position and permit the ready insertion or withdrawal of the shoes from the pockets 19, it being unnecessary, therefore, to use one hand for holding the cover flap open. When the shoe holder is not in use, it is retained in its position in the trunk, as shown in Fig. 2, and the cover flap 32 is held closed. Other and further advantages of my invention will be apparent to those skilled in the art.

While I have shown and described herein my novel shoe holder device as being applied to a wardrobe trunk, yet it is clear that said device may be used in trunks of other types, and, in fact, used in any connection where it is desired to accomplish the objects of my invention.

Although I have shown and described herein in detail one preferred form of my device, yet it is to be understood that the details of construction shown and arrangement of parts illustrated may be variously changed and modified without departing from the spirit and scope of my invention, and I do not wish to be limited to the details of construction and arrangement of parts shown, except as pointed out in the annexed claims.

I claim as my invention:

1. A trunk having two vertical, hinged together sections, one of which is provided with an upright wall and a bottom wall, a cleat secured to said bottom wall and spaced from said upright wall to provide an upwardly opening groove, a shoe holder comprising a base-board adapted to be placed against said upright wall with one of its edges in said groove, fastening members for detachably holding said base-board against said upright wall, and a cover for said shoe holder, said cover having a marginal portion

secured to said bottom wall and extending 25 beneath said cleat.

2. A trunk having two vertical, hinged together sections, one of which is provided with an upright wall and a bottom wall, the latter being provided with an upwardly 30 opening groove, a shoe holder comprising a base-board adapted to be placed against said upright wall with one of its edges in said groove, means adapted to detachably hold said base-board against said upright wall, 35 embracing turn buttons on the latter and holes in said base-board, and a cover for said shoe holder, said cover being secured to said bottom wall and provided with holes for the reception of said turn buttons.

In testimony that I claim the foregoing as my invention, I affix my signature in the presence of two witnesses, this 20th day of November, A. D. 1916.

JOHN H. BARTLETT.
